O. C. ROHDE

TERMINAL CLAMP

Original Filed Oct. 4, 1920

INVENTOR
Otto C. Rohde,
By *John Bond Crampton*,
His attorney.

UNITED STATES PATENT OFFICE.

OTTO C. ROHDE, OF TOLEDO, OHIO, ASSIGNOR TO CHAMPION SPARK PLUG COMPANY, OF TOLEDO, OHIO, A CORPORATION OF DELAWARE.

TERMINAL CLAMP.

Continuation of application Serial No. 414,478, filed October 4, 1920. This application filed January 24, 1921. Serial No. 438,424.

To all whom it may concern:

Be it known that I, OTTO C. ROHDE, a citizen of the United States, and a resident of Toledo, Lucas County, and State of Ohio, have made an Invention Appertaining to Terminal Clamps; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to terminal clamps for electrical conductors, and is intended particularly for use in connection with the lead wires of spark plugs.

The object of my invention is the provision of a simple and inexpensive clamp of the class described, which is adapted to be easily and securely connected in a permanent manner to a cable or wire end and to form a socket capable of releasable yielding engagement with a terminal stud in a simple and efficient manner.

The invention is fully described in the following specification, and while, in its broader aspect, it is capable of embodiment in numerous forms, a preferred embodiment thereof is illustrated in the accompanying drawings, in which,—

Figure 1 is an elevation of the terminal clamp member embodying the invention operatively connecting a spark plug and lead wire. Fig. 2 is an enlarged central longitudinal section of the clamp with the connected wire and terminal stud in full. Figs. 3, and 4 are different views of one member of the clamp. Figs. 5 and 6 are different views of the other member of the clamp. Fig. 7 is an enlarged central longitudinal section similar to Fig. 2 in a slightly modified form of the clamp, and Figs. 8 and 9 are different views of the two members of this modified form of the clamp.

This application includes, as Figs. 7, 8 and 9 thereof, the form of terminal clamp contained in my application filed October 4, 1920, Serial No. 414,478, and is therefore filed as a continuation of said former application as to so much of the matter as is common to both.

Referring to the drawings, 1 designates a conductor wire having the customary cov-

ering 2 of the insulating material, 3 a spark plug, and 4 a terminal stud on the outer end of the central electrode of the spark plug, the stud in the present instance being tapered at its outer end and having a circumferential groove 5.

The terminal clamp embodying the preferred form of the invention comprises a ferrule member 6, which is in the form of a socket to adapt it to be slipped over an end of the wire insulation 2 and has its closed end provided with a central aperture 7 through which the terminal end of the wire 1 may project beyond the insulating material, such wire end being soldered or otherwise intimately connected with the ferrule to form a perfect electrical connection therewith. The side wall of the ferrule member 6 is longitudinally slotted at intervals to form the sides of the ferrule with a plurality of spring fingers for yielding engagement with the wire insulation and having their free ends turned outward to a slight extent, as shown at 8.

The outer member of the clamp has a tubular end or body portion 9, which is longitudinally split at one side, as at 10, to permit a spring contraction or expansion of the member, and the socket of this member is of a size adapting it to snugly receive the ferrule member 6. The body portion 9 is slightly longer than the ferrule 6 and provided near its outer end with an annular internal recess 11 with which the outwardly turned ends 8 of the ferrule member may spring when in register therewith. The member 9 has its outer end contracted to form an annular shoulder 12 to limit the insertion of the ferrule member 6 therein and also to form a restricted socket portion 13 for receiving the outer end of the terminal stud 4, the socket being of a size for the stud to snugly fit therein. The tubular portion 13 is longitudinally slit throughout its length, as shown at 14, to divide such portion into two relatively yieldable segmental leg portions. Each of these leg portions is provided with an inwardly projecting depression or detent 13' disposed in transversely aligned relation and adapted to enter the groove 5 of the stud 4 to yieldingly retain the terminal clamp and stud in assembled relation when the stud is inserted into the socket.

In the form of the invention illustrated in 110

Fig. 7, 8 and 9, the recess 11 is omitted from the outer body member of the clamp and the terminal ends of the inner terminal member 6^a are left straight instead of being turned outwardly, as shown in Fig. 3. In this case the clamp is secured to the wire insulation by turning the free edge of the body member, designated 9^a, in around the adjacent end edges of the ferrule member 6^a to engage the wire insulation and also to force the ends of the ferrule fingers into holding engagement therewith.

It is evident that I have provided a simple and efficient terminal clamp, which is capable of being easily and quickly applied to the end of a lead wire, and which is also capable of being releasably engaged with the terminal stud or nut.

I wish it understood that my invention is not limited to any specific construction, arrangement or form of the parts, as it is capable of numerous modifications and changes, other than those illustrated, without departing from the spirit of the claim.

Having thus described my invention, what

I claim as new, and desire to secure by Letters Patent, is,—

A terminal clamp including a tubular cylindrical body, substantially one-half of which is of reduced diameter to form an internal shoulder between the ends of the body, a ferrule received over an end of a terminal wire and having a closed end and provided with axial slits extending through the opposite end of the ferrule, the larger 30 diametered part of the cylindrical body being engaged over the ferrule with the closed end of the latter abutting said shoulder, and having an axial slit and its free end formed to engage with the free end portions of the ferrule, the part of the body of reduced 40 diameter having a pair of diametrically opposed axial slits to form a pair of legs of substantially semi-circular cross-section, and each of the legs having an inwardly extending detent.

In testimony whereof, I have hereunto signed my name to this specification.

OTTO C. ROHDE.
